UNITED STATES PATENT OFFICE.

ELMER E. JOHNSON AND JOSEPH KERSHAW, OF JOPLIN, MISSOURI.

DISPLAY DEVICE.

Application filed September 7, 1922. Serial No. 586,716.

To all whom it may concern:

Be it known that we, ELMER E. JOHNSON and JOSEPH KERSHAW, citizens of the United States, residing at Joplin, in the county of 5 Jasper and State of Missouri, have invented certain new and useful Improvements in Display Devices, of which the following is a specification.

This invention relates to display devices 10 and more particularly to cards or signs having a fixed member and a movable member.

An object of the invention is the provision of an article that may be used for advertising, as a novelty, as a vehicle signal 15 or the like consisting of the representation of an eye having a movable lid that may be operated to simulate winking.

In the present invention we provide a card having an eye pictured or painted 20 thereon. The card is provided with the curved slot above the eyeball and an eyelid is pivotally mounted on the back of the card and adapted to be lowered through said slot. The eyelid is normally retained in 25 raised position by suitable means and when lowered again assumes its normal position producing the effect of winking.

In the accompanying drawings we have shown one embodiment of the invention. In 30 this showing,

Figure 1 is a front elevation,

Figure 2 is a rear elevation,

Figure 3 is a vertical sectional view on line 3—3 of Figure 1,

35 Figure 4 is a similar view on line 4—4 of Figure 2, and,

Figure 5 is a horizontal sectional view on line 5—5 of Figure 2.

Referring to the drawings, the reference 40 numeral 1 designates generally a card or sheet forming the body portion of the device. This card may be made of any suitable material such as card-board, sheet metal or the like, and may be of any desired

45 size and shape. A picture of an eye is formed on the card in any suitable manner. As shown it consists of an eyeball 2 and a pupil 3. Eyelashes 4 and eyebrows 5 may be painted on the card if desired. The card 50 is provided with a curved slot 6 arranged above the eyeball. An eyelid 7 is arranged on the back of the card, being pivoted at one side on a pin 8. The eyelid, when in raised position, projects slightly through

55 the slot as shown in Figures 3 and 4 of the drawings so that it will assume a position in

front of the eyeball when lowered. A guide member 9 may be arranged in the rear of the eyelid to effect proper operation thereof. As shown this guide member forms a 60 stop for the eyelid on its upward movement and causes the eyelid to pass through the slot 6 when it is lowered. Suitable means are provided for normally retaining the eyelid in raised position. A pin 10 is arranged 65 near the top of the card adjacent the free end of the eyelid and a suitable resilient element is attached to this pin and to the eyelid. In the present instance we have shown a rubber-band 11 arranged over the pin 70 and passed through an opening in the lid. When the lid is lowered the band is stretched as shown in dotted lines in Figure 2 of the drawings causing it to return the eyelid to the normal position as soon as the actuating 75 force is removed. The eyelid is adapted to be lowered by a flexible element 12 which is attached thereto adjacent the free end and passes through a guide member 13 at the bottom of the card. 80

The operation of the device will be apparent from the foregoing description. When the flexible element is pulled a downward pressure is exerted on the free end of the eyelid causing it to lower in front of the eyeball. As soon as the force on the flexible element is released the resilient element 11 returns the eyelid to normal position, thus simulating winking. The guide member 9 limits the upward movement of the eyelid. 90 The lower end of this guide member is secured to the body portion beneath the slot 6 whereby the portion immediately below the slot is flexed rearwardly as shown in Figures 3 and 4 of the drawings. This permits the eyelid to pass over its portion of the card and insures its passage in front of the eyeball when lowered. 95

It is to be understood that the form of our invention herewith shown and described 100 is to be taken as a preferred example of the same, and that various changes in the shape, size, and arrangement of parts may be resorted to without departing from the spirit of the invention or the scope of the subjoined claims. 105

Having described our invention, we claim:

1. In a device of the character described, a substantially flat member having the simulation of an eye thereon, said member being provided with a slot adjacent said eye, an 110

2
eyelid formed of similar material pivotally mounted on the back of said member and projecting through said slot, resilient means for normally retaining said eyelid in raised position, and a flexible element secured to said eyelid remote from said pivot whereby it may be lowered over the adjacent portion of said member to simulate winking.

2. In a device of the character described, 10 a substantially flat member having the simulation of an eye thereon, said member being provided with a slot above said eye, an eyelid formed of similar material pivotally mounted on the back of said member and

projecting through said slot, a guide member secured to the back of said member and embracing the eyelid to limit its upward movement, the lower end of said guide member being secured to said member beneath said slot and adjacent thereto to flex the adjacent portion of said member rearwardly and permit said eyelid to pass through said slot, and means for oscillating said eyelid. 15

20 In testimony whereof we affix our signatures.

ELMER E. JOHNSON.
JOSEPH KERSHAW.
